Jr.

UNITED STATES PATENT OFFICE.

ELMER V. ANDERSON, OF MORRISTOWN, MINNESOTA.

EGG-TURNING DEVICE.

1,136,918.

Specification of Letters Patent. Patented Apr. 27, 1915.

Application filed July 22, 1914. Serial No. 852,420.

To all whom it may concern:

Be it known that I, ELMER V. ANDERSON, a citizen of the United States, residing at Morristown, in the county of Rice and State 5 of Minnesota, have invented certain new and useful Improvements in Egg-Turning Devices; and I do hereby declare the following to be a full, clear, and exact description of the invention, such as will enable others 10 skilled in the art to which it appertains to make and use the same, reference being had to the accompanying drawings, and to the letters and figures of reference marked thereon, which form a part of this specification.

This invention relates to new and useful improvements in devices for turning eggs in incubators and comprises a simple and efficient device of this nature so arranged that 20 a series of eggs may be held upon rollers which may be rotated gradually at such intermittent times as may be best for the successful incubation of the eggs.

The invention comprises a simple apparatus actuated by means of a clock mechanism and consists of various details of construction, combinations and arrangements of parts which will be hereinafter fully described, shown in the accompanying drawings 30 and then specifically defined in the appended claim.

I illustrate my invention in the accompanying drawings, in which:

Figure 1 is a side elevation of a casing 35 of an incubator showing a part broken away to illustrate features of the invention. Fig. 2 is a side elevation showing a clockwork mechanism substituted for the crank for operating the rollers. Fig. 3 is a section on line 3—3 of Fig. 1, and Fig. 4 is an end view of the form shown in Fig. 1, a part of the casing being broken away and a part in section.

Reference now being had to the details 45 of the drawings by numeral, 1 designates the casing of the incubator which may be of any suitable size or shape and mounted within the incubator are racks 1^x having apertures in the opposite sides therein in which a series of rollers 2 is journaled, each having a sprocket wheel 3 fixed to corresponding ends thereof and about which the

sprocket chains 4 pass. In the drawings I have shown two series of rollers, each similarly mounted and each having separate 55 sprocket chains passing about the various sprocket wheels. To the projecting ends of the rollers of the two series are fixed sprocket wheels 5 and about which the rollers 11, shown in Fig. 1 of the drawings, and a 60 sprocket wheel 7 a sprocket chain 6 passes, and 9 is a crank fixed to the shaft 8. Said chain, it will be noted, forms means whereby, as the crank is rotated, the two series of rollers may be simultaneously rotated in the 65 same direction.

In Fig. 2 of the drawings, it will be noted that a boxing 14 is fastened to the under surface of the casing and which is adapted to contain a clockwork apparatus of any 70 suitable mechanism which is operated through the medium of the weight 16.

15 designates a pendulum which is connected to the escapement means which, in turn, regulates the rotary movement of the 75 shaft containing the gear wheel 13 which is geared to the wheel 12 of the clockwork mechanism.

The operation of my invention will be readily understood and is as follows: By 80 the construction shown, the eggs, two of which are shown in Fig. 3, are placed upon the various series of rollers and, whenever it is desired to cause the eggs to be turned, a rotary movement may be imparted to the 85 rollers through the medium of the crank, manually or through the medium of the clockwork mechanism which may be regulated to cause a continuous slow rotary movement to be imparted to the rollers if 90 desired, thus insuring uniform incubation of the eggs.

What I claim to be new is:—

A device for turning eggs in incubators comprising a casing, racks mounted within 95 the casing, rollers journaled in the opposite ends of the racks, driving shafts journaled in opposite ends of the racks and in apertures in the wall of the casing, said racks being supported by the side walls of the 100 casing with a space intervening between the same and the bottom of the latter, sprocket wheels upon said shafts and the rollers at corresponding ends, sprocket wheels fixed

to the ends of the shafts which project outside the casing, rollers pivotally mounted upon the outer face of the casing below and between said sprocket wheels, a driving shaft journaled in suitable bearings underneath the casing; a sprocket wheel upon the driving shaft, a sprocket chain passing about the sprocket wheel upon the project-

ing ends of the shaft and said rollers and the sprocket wheel upon the driving shaft. 10

In testimony whereof I hereunto affix my signature in the presence of two witnesses.

ELMER V. ANDERSON.
